UNITED STATES PATENT OFFICE.

GILES D. MIMS, OF EDGEFIELD, SOUTH CAROLINA, AND SAMUEL K. DUNKLE, OF FINLEYVILLE, PENNSYLVANIA, ASSIGNEES OF ONE-THIRD TO WILLIAM H. KING, OF FINLEYVILLE, PENNSYLVANIA.

RAILROAD-RAIL FASTENER.

SPECIFICATION forming part of Letters Patent No. 599,622, dated February 22, 1898.

Application filed June 11, 1897. Serial No. 640,325. (No model.)

To all whom it may concern:

Be it known that we, GILES D. MIMS, of Edgefield, in the county of Edgefield and State of South Carolina, and SAMUEL K. DUNKLE, of Finleyville, in the county of Washington and State of Pennsylvania, have invented a new and useful Improvement in Railroad-Rail Fasteners, of which the following is a specification.

10 Our invention is in the nature of an improved fastener for connecting together the ends of railroad-rails and also securing them to the subjacent ties; and it consists in the peculiar construction and arrangement of 15 plates, as will be hereinafter more fully described.

Figure 1 is a side view, Fig. 2 a plan view, Fig. 3 a cross-section on line 3 3 of Fig. 2, and Fig. 4 an inverted plan, of the rails with 20 the tie-plate attached.

In the drawings, A A are the two abutting ends of the rails, B B are the subjacent cross-ties, and C C are the tie-plates which constitute the rail-fastener. These tie-plates are 25 made exactly alike, and consist of metal plates which are bent longitudinally, so as to lie against the web portion of the rail at a, the base of the rail at b, and are turned under the edge of the rail-base a little distance 30 at c. At the lower edge of these plates near the ends are formed, integral with the plates, long tongues or wings C' C², which pass under the rail-base and extend across beneath the base to some distance beyond the same and 35 are provided at this point with a spike-hole c' (or c²) at such a distance as will enable the spike d when driven through it to snugly hug and overlap with its head the rail-base. When these plates are applied to the opposite 40 sides of the two abutting ends of the rails, they closely hug and inclose the web and base of the rail, and the spikes that secure each plate to the cross-ties are upon the opposite side of the rail from the plate itself.

The tongues or wings C' C² are so arranged 45 that they lap past each other under the rail at the ends of the plate, and for this purpose the tongues on any one plate are arranged one at the extreme end and the other at a distance from the other end equal to the 50 width of the tongue of the other plate, as seen in Fig. 4.

The upper portion a of the plates, which lies against the web of the rail, is slightly curved or arched away from the web, so as to leave 55 a slight hollow space next to the web. This is for the purpose of allowing a slight spring in the plates when they are clamped against the rails by the bolts e, which pass through the web of the rail, thus holding the nuts 60 firmly against jolting off. The holes in the plates through which these bolts e pass are also slightly elongated longitudinally to the rail to permit endwise expansion and contraction in the rail from variations in temperature. When the ends of the rails are secured in these plates by bolts e and the tongues of the plates are spiked down, a very firm and strong joint is made, acting as fish-plates to hold the ends of the rail in alinement and as 65 tie-plates to secure the rails to the cross-ties with a single construction. With this construction the rails are prevented from spreading under the lateral thrust of the car-wheels, for this spreading action is resisted by the 70 spikes on both sides of the rail—i. e., the lateral movement of the rail in any given direction is resisted both by direct bearing against the spike on one side and by the pull on the tongue from the spike on the opposite side. 75 80

Having thus described our invention, what we claim as new, and desire to secure by Letters Patent, is—

1. A rail-fastener comprising two splice-plates having bolts for fastening them through 85 the web of the rail and each provided with integral tongues extending beneath the rail-base to the opposite side from the one on which

the plate lies and there provided with spike-holes substantially as and for the purpose described.

2. A rail-fastener comprising two splice-
5 plates having a concaved upper part *a* lying
against the web of the rail and provided with
bolt-holes a lower portion *b* extending over the
rail-base an undeturned edge *c* lying under
the rail-base, and two perforated tongues ex-
10 tending beneath the rail-base to the opposite
side of the rail from the one on which the

plate lies and adapted to receive spikes sub-
stantially as and for the purpose described.
